Patented June 13, 1922.

Inventor

BRINAY SMARTT,

By *E. G. H. Smartt*
Attorney

UNITED STATES PATENT OFFICE.

BRINAY SMARTT, OF INDIANAPOLIS, INDIANA, ASSIGNOR OF ONE-HALF TO W. J. KEARNEY AND ONE-FOURTH TO HASSEL D. ROBINSON, BOTH OF INDIANAPOLIS, INDIANA.

SHOCK ABSORBER.

1,419,320.

Specification of Letters Patent. Patented June 13, 1922.

Application filed August 17, 1921. Serial No. 492,949.

To all whom it may concern:

Be it known that I, BRINAY SMARTT, residing at 544 Indiana Ave., in the city of Indianapolis, county of Marion, State of Indiana, and a citizen of the United States, have invented certain new and useful Improvements in Shock Absorbers, of which the following is a specification.

The object of my invention is to provide a novel construction of shock absorber, which shall be extremely simple in construction, thoroughly efficient in use, and entirely practical from a manufacturing and engineering standpoint.

With this object in view, the invention resides in the novel construction, combination, and arrangement of co-operating parts, as will be hereinafter fully described in the specification, summarized in the claim, and illustrated in the accompanying drawing.

The drawing, forming part of my specification, discloses the preferred embodiment of my invention, and like reference characters designate corresponding parts throughout the several views. Briefly described:

Figure 1 is a view in side elevation of my shock absorber;

Figure 2 is a transverse sectional view on the line 2—2, Fig. 1; and

Figure 3 is a fragmentary view, partly in section, partly in side elevation, of the device.

Referring, now, in detail to the drawing: 35 1 designates a casing, preferably circular in cross section, as shown, and provided, at diametrically opposite points in its peripheral wall, with two openings 2, 2; adjacent said openings, with two pairs of ears 3, 3, the two ears in each pair being parallel and drilled to provide aligned openings 4; and, at diametrically opposite points, with two outward-projecting, open-ended, tubular extensions 5, 5 communicating, through the inner open ends thereof, with the interior of the casing 1. Advantageously, the casing 1 and the extensions 5, 5 are integral, and, for this purpose, may be formed as a casting. A removable face-plate 11, formed as 50 a disk, may be suitably secured, as by screws, to the casing 1, to close the chamber thereof.

The extensions 5, 5 are exteriorly screw-threaded toward their outer ends, for threaded engagement with screw caps 6, 6.

55 Slidably mounted in each of said exten-

sions 5, 5 is a hollow cylindrical member or barrel 7, open at its outer end, but closed at its inner end (as shown at 8). Preferably, said barrels are integrally united, at adjacent ends, by a reduced tongue or bridge 9. That is to say, the barrels 7, 7 and the tongue 9 are preferably formed as a cylindrical casting, the casting being axially bored from the ends thereof to a point near the longitudinal center thereof, the solid central portion being cut away, on both sides, to provide an integral tongue or bridge 9, having parallel, flat faces. This central cut-away portion, forming the bridge 9, is provided with curvilinear end walls 10, 10.

Projecting within the chamber of each cylindrical member or barrel 7 is a coiled compression spring 18, one end thereof bearing against the closed end of said barrel and the other end against the cap 6.

Fulcrumed between the two ears of each pair of ears 3, 3, is a bell-crank lever 12, provided, for this purpose, at the point of union of the longer and shorter arms thereof, with an opening adapted to register with the openings 4 in the ears 3, 3, a fulcrum-pin 13 passing through said registering openings.

The shorter arms 14 of said levers project, 85 in the assembled position of the parts, into the casing, through the openings 2, 2 in the casing 1, and are provided, at their free ends, with overlapping yokes 15, in which the bridge or tongue 9 is received, one of said 90 yokes lying against the flat faces of said tongue 9, and said yokes having curvilinear ends, all as clearly shown in Figs. 1 and 2.

In use, the longer arms of the bell-crank levers 12, 12 are suitably secured, at their otherwise free ends, to the vehicle body and the vehicle spring, as shown at 16 and 17. In operation, vibration moves the longer arms of the two bell-crank levers 12, 12 toward each other, which will rock the shorter 95 arms 14, 14 of said levers toward the left in Figs. 1 and 3, and the curvilinear edges of the yokes 15, 15, bearing against the curvilinear walls 10, 10 at the left in Figs. 1 and 2, will force the twin barrels 7, 7 to the left 100 in said figures, thereby compressing the left-hand spring 18. Upon rebound, the twin barrels 7, 7 move in the reverse direction, against the influence of the right-hand spring 18. 110

Having thus fully described my invention, what I claim as new and desire to secure by Letters-Patent is:

In a shock-absorber, a casing having two tubular, open-ended extensions, means normally closing the outer open ends of said extensions, a cylindrical member extending diametrically across said casing and projecting into said extensions and axially bored from the ends thereof to a point near the longitudinal center thereof, to form two connected twin barrel portions, the longitudinally-central portion of said cylindrical member being cut away on two opposite sides

to form a reduced bridge having parallel flat faces, coiled compression-springs within said extensions and projecting into said barrel-portions, and bell-crank levers fulcrumed to said casing with the shorter ends thereof projecting into the casing and having overlapping yoke-terminals, one thereof lying against the flat faces of said bridge, and said yoke-terminals having curvilinear edges bearing against the curvilinear end walls of said bridge.

In testimony whereof I hereunto affix my signature.

BRINAY SMARTT.
